2,437,300

TELEVISION AND SOUND TRANSMITTING
SYSTEM

Emile Labin, New York, N. Y., assignor to Federal
Telephone and Radio Corporation, New York,
N. Y., a corporation of Delaware

Application August 25, 1944, Serial No. 551,201

7 Claims. (Cl. 178—5.8)

1

This invention relates to television transmitting systems and more particularly to a system for transmitting a multiple of television programs.

Television broadcasting systems are being developed along substantially the same lines as the standard A. M. (amplitude modulation) broadcasting systems. The method used is the following: In the larger centers of population, New York city for example, the studios of the several television broadcasting stations are situated conveniently to the program originating sources. From these studios the programs are piped by line to the respective transmitting stations which are located primarily for maximum populated area coverage and which transmit on individual authorized frequencies. At the receiving end the listener, of course, separates the various stations by frequency tuning.

While this system of broadcasting has proved entirely satisfactory for the lower frequencies, the same advantages do not necessarily follow at the higher frequencies employed in television. In fact, at these higher frequencies several major disadvantages arise. To give a few examples:

There can only be a limited number of optimum transmitting locations about the area to be served, and since height of the transmitting antenna in such area is all important at the higher frequencies, those stations not possessing these important locations are at a serious disadvantage with respect to their competitors. In New York city for example, there is only one Empire State building dominating in height the entire city and centrally located. The television broadcasting company controlling this location enjoys, therefore, a monopoly which even a considerably larger amount of power at other locations cannot overcome.

The listener's receiver in an area served by several broadcasting stations is also at a distinct disadvantage with the existing system. With the various transmitting stations located at different compass points with respect to the receiving location, it is not possible for a single simple receiving antenna to be operated at maximum efficiency due to the problem of reflections from nearby buildings and other multi-path transmissions. This is especially true with television, although not much less so with music and voice broadcasting. The practical reduction of these reflection effects entails the use of a directive antenna which when placed in the best position with respect to one transmitter might be quite unsatisfactory for receptions from another trans-

2

mitter. Hence, in order to receive all the stations, in addition to the normal receiving tuning, a definitely impractical rotation of the antenna or a switching antenna system is necessary.

5 In addition to the above-mentioned disadvantages there are still others such as the duplication of transmitting apparatus and transmitting antenna towers, and the reduced efficiency of duplicate operation.

10 It is an object of this invention to provide a multiple television broadcasting system which overcomes the above-mentioned disadvantages of existing and other heretofore proposed broadcasting systems.

15 Another object is to provide a multiple television broadcasting system incorporating the unique advantage of ultra-high frequency pulse transmission.

Another object of the invention is to provide 20 a multiple television transmitting system for transmitting all of the programs of a plurality of television transmitters over antennas located at a common advantage point for the area served.

25 A further object is to provide a method and means for television transmission whereby the synchronizing signals and the sound signals are transmitted on a multichannel carrier separate from the picture carrier; and in the case of multiple television programs, each picture program is 30 transmitted on a separate carrier frequency while the synchronizing signals and the sound signals for each picture program are transmitted over a single multi-channel carrier.

Still another object of the invention is to provide 35 a television transmitting system so arranged that the entire amplitude swing of the transmitter may be substantially fully employed for the picture signals alone.

The different carriers of the multiple television 40 system are broadcast according to my invention over their respective antennas which I locate at a single vantage point such as at the top of the highest building of a city or on a tower located at some other high elevation within the area served. The antennas preferably are the omnidirectional type although they may have certain 45 directional characteristics if desired. By this arrangement no one transmitter has the unfair advantage of having an antenna located much higher than another.

50 By grouping the several transmitters the total transmitting equipment is simplified by combining certain operations. For example, instead of transmitting the sound accompanying each picture over a separate sound transmitter at a frequency close to the picture

carrier frequency, I concentrate all sound transmission in one single multi-channel transmitter. In addition, I utilize the same synchronizing signals for all of the picture transmitters and by transmitting the synchronizing signals separate from the picture signals, the entire amplitude swing of the picture transmitters can be fully employed for picture signals only. Further, the synchronizing signals being common to all picture transmitters serve to synchronize receivers for selective reception of any desired one of the picture programs as well as for the corresponding sound channel.

For a further understanding of the invention, reference may be had to the following detailed description to be read in connection with the accompanying drawings, in which

Fig. 1 is a block diagram of a multiple television transmitting system according to my invention, and

Fig. 2 is a graphical illustration used in explaining the operating principles of the system.

In Fig. 1, an illustrated example of a multiple television system is shown according to the principles of my invention. The system is shown for three television transmitters although a greater or lesser number may be provided as will be made clear from the following detailed description. Three sound transmitting channels 1, 2 and 3 of a multi-channel transmitter 4 are associated with the three picture transmitters 5, 6 and 7. The transmitters 4, 5, 6 and 7 operate on different carrier frequencies f_0 , f_1 , f_2 , and f_3 , as indicated, the outputs thereof being applied to antennas 8, 9, 10 and 11, respectively, all of the antennas being mounted on a common tower 12 located at a vantage point in the area served.

The same synchronizing signals are employed for the different picture transmitters whereby the video signals of the different picture transmitters are all synchronized alike. The synchronizing pulses have as their basis the pulses 13, graph a of Fig. 2, produced by base pulse producer 14. The pulses 13 are preferably of a repetition frequency desired for the horizontal synchronizing pulses although this is not essential. To obtain the horizontal synchronizing pulses 15, graph b, the pulses 13 are applied to a horizontal synchronizing pulse shaper 16. The pulses 15 are shown to be of a given width whereby they are distinguished from other width pulses provided for other channels. To produce the vertical synchronizing pulses, the pulses 13 are applied to a pulse divider 17 whereby the pulse repetition frequency is reduced to the desired frequency for the vertical synchronizing pulses which correspond to the number of picture frames per second. The pulse divider 17 may be arranged to shape the output pulse thereof for distinguishing the vertical synchronizing pulses from the horizontal synchronizing pulses but as shown I have included a separate shaper 18 for this purpose. The output pulses of shaper 18 are of a width indicated by vertical synchronizing pulse 19 of graph c whereby it may be selected by pulse width discrimination from the other pulses of the multi-channel carrier.

While this system herein shown uses the so-called "horizontal and vertical synchronizing signals" it will be recognized that other types of synchronizing signals may be used such as where a picture scanning method different from the line scanning method is employed. Therefore, where the expression "synchronizing signals" or "synchronizing pulses" are used in the appended

claims, such expression is to be regarded broadly and not as limited to horizontal and vertical synchronizing signals.

For interlacing, the vertical pulses for successive frames may be differently distinguished as to pulse width or otherwise varied. However, for sake of simplicity the interlacing feature is not herein shown since such showing is believed not necessary to an understanding of the multiple television transmitting principles of my invention.

For multi-channel transmission the pulses 13 are applied to a pulse multiplier 20 for producing a proper number of pulses per second for the different channels required. As shown by graph d, the multi-channel pulses 21 are four times the number of base pulses 13. This provides three channels for sound transmission and one channel for transmission of the horizontal and vertical synchronizing pulses. By increasing the number of multi-channel pulses 21 additional channels may be added. This may be accomplished by maintaining narrow width pulses and decreasing the time intervals between pulses of successive channels.

According to the multi-channel feature employed in this system the sound signals from sources 22, 23 and 24 are so chopped up relative to a base taken at a negative potential at or below the maximum negative signal value that interleaved segments of signal energy are obtained therefrom for modulation of the pulses 21 at time modulator 25 according to some principle of time modulation. In the example shown this is accomplished by applying pulses 13 to a shaper 26 which widens the pulses to the width of the signal segment desired. These wide keying or chopper pulses are applied for channel 1 through a delay device 27 whereby the chopper pulses for channel 1 are retarded an amount t_1 causing them to coincide with the pulses of channel 1 as indicated in graphs d and e. The keyer pulses of shaper 26 thus retarded are applied to an amplifier 28 to which the signal energy from source 22 is applied. The amplifier 28 is normally blocked to the signals from source 22 but is keyed to pass the signal energy in response to the keyer pulses. The amplifier 28 thus selects pulse segments 29 of the signal energy for the duration of each keyer pulse. The pulse segments 29 of graph e for channel 1 are shown, for example, of a minimum value corresponding to a maximum negative value of signal energy. The pulse segments 30 for channel 2 are shown in graph f timed at interval t_2 from pulses n and as decreasing in amplitude according to the signal energy indicated by envelope 31 from source 23. Likewise pulse segments 32 of graph g for channel 3 is timed an interval t_3 from pulses r and are shown to represent progressively increasing values according to signal envelope 33 for source 24.

The interleaved pulse segments 29, 30 and 32 are applied as a train of pulses to time modulator 25 to which the train of pulses 21 are also applied. Since pulse segments 29 coincide with the pulses of channel 1, the pulses thereof are displaced in time position according to the respective amplitude of the corresponding pulse segments 29. Any T. M. modulator may be used at 25 that is capable of displacing pulses according to the instantaneous values of signal energy either by retardation or by a translation process. For retardation of pulses a delay network may be employed where the inductance includes one

or more coils having iron cores whereby the inductance thereof may be varied according to the amplitude of the applied signal energy. Another example of a T. M. modulator is a system for making the pulses 21 of generally saw-tooth shape and to clip such shaped pulses by a clipper gate the clipping levels of which are controlled by signal energy. The resulting output of the clipping operation is then differentiated to produce pulses which vary in time position relative to the input pulses according to the amplitude of the applied signal energy. For a more complete discussion of these types of T. M. modulators and also of the multi-channel system employing them, reference may be had to my Patent No. 2,408,077.

The graph *h* indicates the employment of a T. M. modulator adapted to retard the pulses 21 according to the amplitude of pulse segments 29, 30 and 32. The minimum amplitude represented by pulse segments 29 are shown to cause a pulse displacement $t + \Delta t$. The displacement t is that displacement normally produced by the modulator in the absence of a modulating signal segment as indicated with reference to pulse *n*, graph *h*. Since the pulse segments 30 decrease in amplitude from left to right in graph *f*, the corresponding retardation is greatest for the pulses 2 at the left and decreased proportionately to the right as shown in graph *h*. Since the pulse segments 32 increase in amplitude from left to right in graph *g*, the corresponding time displacement increases from left to right in graph *h*. It will be understood, of course, that the pulses of graphs *e*, *f* and *g* represent only a small portion of the signal waves of the three signal sources, the different signal values being given for sake of variety of illustration.

The output pulses of time modulator 25 are applied to mixer 34 together with the horizontal and vertical pulses 15 and 19 from shapers 16 and 18 respectively. This results in the addition of the pulse potentials in certain instances as indicated in graph *h* for pulses *n*. The mixer is of known character having a limit clipping level as indicated at 35 whereby the super-imposed pulses of graph *h* are eliminated leaving for transmission the pulse train indicated in graph *i*. This pulse train includes the horizontal synchronizing pulses 15, the vertical synchronizing pulses 19 and the multi-channel pulses 1, 2 and 3. This train of multi-channel pulses is applied from the mixer 34 to the transmitter 4 whereby the pulses are transmitted on a carrier frequency f_0 over antenna 8.

The picture video signal of graph *j* includes horizontal blanking pulses HB and vertical blanking pulses VB which interleave with lines of picture signals 36 as indicated. The horizontal blanking signals HB are produced from pulses 15 by a shaper 37 while the vertical blanking pulses VB are produced from pulses 19 by the shaper 38. These shapers may be of any known character and may include means for varying the time positions of the output pulses thereof relative to the input synchronizing pulses, so that the blanking pulse occurs a small interval ahead of the corresponding synchronizing pulse. This relationship is indicated in graphs *i* and *j*.

The horizontal and vertical synchronizing pulses 15 and 19 are applied together with the blanking pulses HB and VB to each of the picture cameras 39, 40 and 41 to control alike the picture scanning of all the television cameras, the graph *j* serving as an example of the output of each television camera. It will be observed that since

the horizontal and vertical synchronizing pulses are not super-imposed on the blanking pulses of the video signal, the entire amplitude swing of the transmitters 5, 6 and 7 may be employed by the picture signals. In the systems hereinbefore providing a composite video signal the picture component was limited to a part only of the amplitude capacity of the transmitters so as to reserve a part thereof for the horizontal and vertical synchronizing signals.

While the video signal shown is of the character obtained by line scanning it should be understood that I do not intend to limit my invention to line scanning because, clearly, my invention is equally applicable to other methods of scanning, such for example, as "spot scanning."

The video signals from cameras 39, 40 and 41 are applied to transmitters 5, 6 and 7 where they are converted for transmission on carriers of frequencies f_1 , f_2 , and f_3 , respectively for application to antennas 9, 10 and 11.

Each television receiver is arranged to receive simultaneously two carriers, the multi-channel carrier on frequency f_0 , and one of the other carrier frequencies transmitted over antennas 9, 10 and 11. The receiver is tunable as to the different frequencies f_1 , f_2 , and f_3 while reception of the multi-channel carrier f_0 is maintained for the reception of any one of the others. In this way the receiver is maintained in synchronism regardless of the tuning from one to another of the three or more television programs. The tuning of the receiver also includes means for tuning from one sound channel to another in accordance with the picture program selected by frequency tuning. For a more complete discussion of the television receiver principles reference may be had to my co-pending application, Serial No. 551,203, filed August 25, 1944.

From the foregoing description it is readily apparent that my invention provides maximum usage of the optimum transmitting location of each service area. It also greatly minimizes the troublesome reflection problem encountered in television reception since each receiver may be provided with a directional antenna installed in the best possible relationship with respect to the antenna tower 12. This provides for maximum and equal reception quality from all of the television transmitters.

In addition to the advantage of maximum and equal reception quality, greater efficiency and lower cost operation results due to the combining of the common transmitting operations of the several television transmitting systems. For example, there is the elimination of several duplications of equipment in both the transmitter and antenna installations as is clear from the foregoing description.

While I have described herein the principles of my invention in connection with a specific embodiment, it is to be clearly understood that this description is made only by way of example and not as a limitation on the invention and the scope of the accompanying claims.

I claim:

1. A television transmitting system comprising means for producing horizontal and vertical synchronizing pulses for use with each of a plurality of television channels, means for producing lines of different picture signals for each channel in synchronism with said horizontal and vertical synchronizing pulses, means to produce pulses modulated according to sound signals accompanying at least one of said picture signals, means to

transmit said picture signals on individual carrier frequencies, and means to transmit on another carrier frequency said horizontal synchronizing pulses, said vertical synchronizing pulses and said sound modulated pulses.

2. A television transmitting system comprising means for producing a train of vertical synchronizing pulses of a desired repetition frequency, means for producing a train of horizontal synchronizing pulses at a repetition frequency equal to a given multiple of the repetition frequency of said vertical synchronizing pulses, means for producing lines of different picture signals in synchronism with said horizontal and vertical synchronizing pulses means for producing a third train of pulses of the repetition rate of said horizontal pulses timed a given interval relative to said horizontal synchronizing pulses, means to time modulate said third train of pulses according to sound signals accompanying said picture signals, means to transmit said picture signals on individual carrier frequencies, and means to transmit on another carrier frequency said horizontal synchronizing, said vertical synchronizing and said time modulated pulses.

3. A multiple television transmitting system comprising means for producing a train of horizontal and vertical synchronizing pulses, at least two separate picture line producing means each responsive to said train of synchronizing pulses for producing lines of picture signals for a television program, means for multi-channel modulating a train of pulses according to the sound accompanying each picture program, means for transmitting the picture signals of one of said line producing means on one carrier frequency, means for transmitting the picture signals of the second line producing means on a second carrier frequency, means to transmit on a third carrier frequency said horizontal and vertical synchronizing pulses and the train of sound modulating pulses.

4. A multiple television transmitting system comprising means for producing a train of vertical synchronizing pulses of a desired repetition frequency, means for producing a train of horizontal synchronizing pulses at a repetition frequency equal to a given multiple of the repetition frequency of said vertical synchronizing pulses, at least two picture line producing means each responsive to said vertical and horizontal synchronizing pulses to produce lines of picture signals for a television program, means for producing a third train of pulses at the repetition rate of said horizontal synchronizing pulses, means to retard differently the pulses of said third train to produce different series of pulses timed different intervals relative to said horizontal synchronizing pulses, means for modulating a characteristic of the pulses of the different series according to the sound signals accompanying the different television programs, means for transmitting the picture signals of one of said producing means on one carrier frequency, means for transmitting the picture signals of the second of said line producing means on a second carrier frequency, and means for transmitting said horizontal and vertical synchronizing pulses and each series of said sound modulated pulses on a third carrier frequency.

5. A multiple television transmitting system comprising a plurality of television transmitters

operating on different carrier frequencies, each transmitter having means for producing lines of picture signals separated by horizontal and vertical blanking intervals, means for producing a single train of horizontal and vertical synchronizing pulses for controlling the picture line producing operations of said transmitters, a multi-channel transmitter operating on still another carrier frequency having separate sound channels corresponding to the picture program of said television transmitters, and at least one further channel for transmission of said horizontal and vertical synchronizing pulses for synchronizing receivers for reception of any desired one of the programs transmitted from said television transmitters.

6. A method of transmitting a television program comprising producing horizontal and vertical synchronizing signals for use with each of a plurality of television channels, producing lines of different picture signals for each channel in accordance with the timing of said horizontal and vertical synchronizing signals, producing pulses a characteristic of which is modulated according to sound signals accompanying said picture signals, transmitting said picture signals on one carrier frequency, and transmitting on another carrier frequency said horizontal synchronizing signals said vertical synchronizing signals and said sound modulated pulses.

7. A method of transmitting a plurality of television programs comprising producing a train of horizontal and vertical synchronizing pulses, producing lines of picture signals for each of the television programs in synchronism with said train of horizontal and vertical synchronizing pulses, producing a train of pulses, modulating a characteristic of different series of said train of pulses according to the sound accompanying the different television programs, transmitting the picture signals of said plurality of programs on different carrier frequencies, and transmitting said train of horizontal and vertical synchronizing pulses together with the sound modulated pulses for said plurality of programs on still another carrier frequency.
